UNITED STATES PATENT OFFICE.

MATILDA E. BARNET, OF PHILADELPHIA, PENNSYLVANIA.

DESIGN FOR A MASSAGE-TOOL.

SPECIFICATION forming part of Design No. 30,230, dated February 21, 1899.

Application filed January 26, 1899. Serial No. 703,514. Term of patent 7 years.

To all whom it may concern:

Be it known that I, MATILDA E. BARNET, a citizen of the United States, residing in Philadelphia, Pennsylvania, have invented a certain new and useful Design for a Massage-Tool, of which the following is a specification.

My design for a massage tool or paddle is clearly illustrated in the accompanying drawings, in which—

Figure 1 is a perspective view. Fig. 2 is a plan view. Fig. 3 is a side view; and Figs. 4, 5, and 6 are transverse sectional views on the lines 4 4, 5 5, and 6 6, respectively.

The essential features of the design are the curve of the body, the taper of one end, and the rounding of the opposite end.

The tool or paddle has one side a convexed and the other side a' concaved, and the end a^2 is slightly tapered and rounded, as shown, while the end a^3 is tapered to a blunt point and rounded. The edges of the tool are also rounded, producing the design as illustrated.

I claim—

The design for a massage tool or paddle as herein described and as shown in the accompanying drawings.

In testimony whereof I have signed my name to this specification in the presence of two subscribing witnesses.

MATILDA E. BARNET.
